UNITED STATES PATENT OFFICE.

JOHN W. TEMPLIN, OF KOKOMO, INDIANA, ASSIGNOR OF ONE-HALF TO JAMES EDWARD HALL, OF KOKOMO, INDIANA.

REAPER AND BINDER.

Application filed July 29, 1921. Serial No. 488,359.

To all whom it may concern:

Be it known that I, JOHN W. TEMPLIN, a citizen of the United States, residing at Kokomo, in the county of Howard and 5 State of Indiana, have invented a new and useful Reaper and Binder, of which the following is a specification.

This invention relates to motor operated agricultural machines, and more particularly to a novel form of means for propelling the machine from a point adjacent to the rear thereof, thereby eliminating mashing down of the grain during the cutting 10 operation.

15 An object of the invention is to provide a propelling means which will not only move the machine over the ground surface on which the same is supported, but may be employed for guiding or steering the machine in the desired direction.

With the foregoing and other objects in view which will appear as the description proceeds, the invention resides in the combination and arrangement of parts and in 25 the details of construction hereinafter described and claimed, it being understood that changes in the precise embodiment of the invention herein disclosed, may be made within the scope of what is claimed, without departing from the spirit of the invention.

Referring to the drawings:

Figure 1 is a plan view of a device constructed in accordance with the present invention.

Figure 2 is a rear elevational view, parts thereof being shown in section.

Figure 3 is a side elevational view of the same.

40 Referring to the drawings in detail, the device comprises a frame which is formed of the side rails 5 and end rails 6 and 7 respectively, the side rails 5 being shown as having their rear ends extending inwardly 45 where the same provide supporting means for the circular supporting ring 8.

This supporting ring 8 has connection with the rearwardly extending portions 9 of the arm 5, in any suitable manner, the 50 supporting ring being provided with a flange 10 which provides a rest for the ring gear 11, through the medium of which the machine may be guided.

A vertical rod 12 has connection with the

supporting ring 8 and carries a pinion 13 55 on the lower end thereof, which pinion meshes with the teeth of the ring gear 11, so that movement of the rod 12 and pinion 13 results in a relative movement of the ring gear 11 to accomplish the steering of 60 the machine. Supported on the upper end of the rod 12 is a hand wheel 14 which is disposed in easy access of the operator of the machine.

Having connection with the ring gear 11, 65 is an upwardly extending bracket 15 in which bracket is supported an axle 16 on which the bull wheel 17 of the machine is mounted to freely rotate, the bull wheel 17 being however provided with a beveled 70 gear 18 which is in mesh with the beveled pinion 19 that is also carried by the bracket 15. The pinion 19 is mounted on the shaft 20 that extends upwardly and carries a pinion 21 on the upper end thereof, which pinion 21 is in mesh with the pinion 22 supported adjacent to the pinion 21, the shaft 75 on which the pinion 22 is supported being indicated at 23.

The pinion 24 is mounted on the upper 80 end of the shaft 23 and is in mesh with the beveled pinion 25 mounted on one end of the horizontal shaft 26 that is carried in suitable bearings provided in the upper ends of the bars 27 and 28 respectively. 85

A motor indicated at 29 is also mounted on the frame of the machine and carries a pinion 30 on one end of the rotor shaft thereof, the pinion 30 being provided to transmit movement to the sprocket wheel 90 31 through the medium of the chain 32 which operates over the sprocket wheels.

As shown, the sprocket wheel 31 is mounted on one end of the shaft 26 to impart rotary movement thereto, which in turn imparts rotary movement to the various pinions and gears as described, for accomplishing the movement of the machine.

95 From the foregoing it will be seen that as the motor is operated, the bull wheel 17 is caused to revolve, moving the machine to its work. The machine may be simultaneously guided through the bull wheel 17 by manipulating the hand wheel 14 to revolve the ring gear 11 in a horizontal 100 plane.

105 As shown, supporting wheels 33 and 34 are mounted at the forward end of the ma-

chine, the supporting wheel 34 being mounted in advance of the supporting wheel 33 at the opposite side of the frame.

Due to the manner of positioning the supporting wheel 34, it will be seen that the endless conveyors and aprons of a binder may be positioned on the platform 35 of the machine, in any well known manner, whereby the machine may deliver material 10 to the binder.

Having thus described the invention, what is claimed as new is:—

In an agricultural machine, a frame including side and end bars, the side bars having their rear ends extending at angles towards each other, a supporting ring secured to the rear ends of the side bars, said supporting ring including a circular flange, a supporting member contacting with the

under surface of the flange, a ring gear on 20 the supporting member and contacting with the upper surface of the flange to secure the supporting member to the frame, a pinion in mesh with the ring gear for rotating the supporting member, a wheel mounted in the 25 frame to move therewith, a beveled pinion carried by the frame, and a beveled gear carried by the wheel, whereby movement is imparted to the wheel, and means for imparting movement to the beveled pinion. 30

In testimony that I claim the foregoing as my own, I have hereto affixed my signature in the presence of two witnesses.

JOHN W. TEMPLIN.
